UNITED STATES PATENT OFFICE.

GEORGE ALFRED HAROURT, OF TORONTO JUNCTION, CANADA.

OIL-CAN.

No. 820,784.

Specification of Letters Patent.

Patented May 15, 1906.

Application filed April 11, 1905. Serial No. 255,049.

To all whom it may concern:

Be it known that I, GEORGE ALFRED HAROURT, of Toronto Junction, in the county of York, in the Province of Ontario, Canada, 5 have invented certain new and useful Improvements in Oil-Cans and Liquid-Receptacles, of which the following is a specification.

My invention relates to improvements in oil-cans and liquid-receptacles; and the object of the invention is to provide an improvement in the interior construction of the can whereby the oil or other liquid may be prevented from forcing the cork out of the can should the can be suddenly tilted, or, if upright, subjected to extreme vibration, as in trains, cars, or other vehicles, and thereby prevent the waste of oil not only under such conditions, but also if no cork is utilized to close the neck of the vessel; and it consists, essentially, of an oil-can having a conical top and suitable neck at the apex of such top, a supplemental top located within the vessel and extending upwardly into the conical top and provided with a neck at its apex, a reverse saucer-shaped deflecting-plate held supported above the neck of the inner top, the said inner top having openings on the outer edge and shields extending above such openings, the parts being otherwise arranged and constructed in detail as hereinafter more particularly explained.

Figure 1 is a perspective view of an oil-can partially broken away to exhibit the parts involved in my invention. Fig. 2 is a vertical section through the oil-can.

In the drawings like letters of reference indicate corresponding parts in each figure.

A is the body of the can, and B the conical shaped top, provided with a neck C, into which the cork D is inserted, and E is a handle.

F is a supplemental interior top which is cone shape in form and provided with a neck G, edge openings F', and shields F'', open at the sides, which extend over such openings.

H is a saucer-shaped deflecting-plate which is reversely placed above the neck G and is held at a distance from such neck by suitable side stems I, which leave openings I', through which the liquid is free to pass.

J is a cross-shaped top for the center of the saucer-shaped deflecting-plate H, such top J being designed to support the funnel should it extend down freely into the neck instead of being supported by the neck, and by this means the bottom of the funnel is prevented

from resting on the plate H, which would retard the flow of liquid when the can is being filled.

A can constructed as I have described will 60 not when tilted or subjected to undue vibration when in trains or cars allow of the oil to splash up against the cork and accidentally force it from its seat, and thereby probably cause its loss. The reason of this will be ap- 65 parent, as the splashing will pass up against the inner top and onto the deflecting-plate, which will cause it to pass downwardly over the top and through the openings F'. The shield F'' will prevent the splash of the oil up- 70 wardly through the openings F' while allowing the oil to pass down through them when it splashes onto the inner top F.

The utility of the interior construction of my can will now be understood to those familiar with the deficiency of the ordinary cans as at present constructed. 75

What I claim as my invention is—

1. In an oil-can and liquid-receptacle, the combination with the can-body having a suit- 80 able top and orifice therein, of a reverse saucer-shaped deflecting-plate located below the orifice and suitably supported, and an open support secured to the center of the top of the deflecting-plate immediately below the 85 orifice as and for the purpose specified.

2. In an oil-can and liquid-receptacle, the combination with the can having a conical top and an orifice at the apex of the same, of a cone-shaped inner or supplemental top pro- 90 vided with a suitable orifice at the apex there- of and a saucer-shaped deflecting-plate suitably supported above the orifice as and for the purpose specified.

3. In an oil-can and liquid-receptacle, the combination with the can having a conical top and an orifice at the apex of the same, of a cone-shaped inner or supplemental top pro- 95 vided with a suitable orifice at the apex there- of, and a saucer-shaped deflecting-plate located centrally above the orifice and sup- 100 ports secured to the neck of the orifice and to the bottom of the deflecting-plate as and for the purpose specified.

4. The combination with the can having a 105 conical top and a central orifice, of an interior supplemental conical top having an orifice at its apex, and an orifice at its edge and a de- deflecting-plate suitably supported above the central orifice and leaving an opening for the 110 passage of the liquid, and a shield located above the side orifice and leaving an opening

for the passage of the liquid as and for the purpose specified.

5. In an oil-can and liquid-receptacle, a deflecting-plate, a cone-shaped supplemental top having a central orifice and means for supporting the deflecting-plate above the orifice as and for the purpose specified.

6. In combination a conical supplemental

top provided with openings at the edge having shields therefor and a central orifice and a deflecting-plate suitably supported above the same as and for the purpose specified.
